US00D843380S

(12) **United States Design Patent** (10) **Patent No.:** **US D843,380 S**
(45) **Date of Patent:** **** Mar. 19, 2019**

(54) **ARTICULATING ARM**

(71) Applicant: **Southco, Inc.**, Concordville, PA (US)

(72) Inventors: **Benjamin Gerald Lindo**, Philadelphia, PA (US); **Glenn Eric Anderson**, Malvern, PA (US)

(73) Assignee: **SOUTHCO, INC.**, Concordville, PA (US)

(**) Term: **15 Years**

(21) Appl. No.: **29/643,972**

(22) Filed: **Apr. 13, 2018**

CLAIM

The ornamental design for an articulating arm, as shown and described.

DESCRIPTION

FIG. 1 is a front, right-side perspective view of an articulating arm;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, right-side perspective view thereof shown in a lowered position.

(Continued)

The broken lines in FIGS. 1-8 illustrate portions of the articulating arm that form no part of the claimed design.

1 Claim, 8 Drawing Sheets
